DISPENSING AND SPREADING SUPPORT
FOR HAIRPINS AND THE LIKE

Charles T. Calafiore, Baltimore, Md.

Application January 10, 1945, Serial No. 572,159

6 Claims. (Cl. 132—1)

1

This invention relates to a dispensing and spreading support for hairpins and the like.

The present embodiment of the invention is designed for dispensing and spreading the form of hairpins that are commercially known as "bobby pins" which are in the nature of spring-clamps that individually and respectively engage with locks of hair and retain such engagement by spring-generated friction. Such hairpins are properly formed to be slid into engagement with hair-locks of limited thickness; but if and when desirable that locks of greater thickness be engaged by the respective bobby-pins, it is necessary (in absence of a supported opener) to use both hands of the user for holding and opening or spreading, and this is inconvenient and inefficient, for one hand is necessarily occupied in holding the hair-lock to be clamped by the bobby-pin.

Therefore, a primary object of the invention is to provide a finger-supported device, or finger-carried support which is also a spreader to increase the distance between prongs of the hair-clamping hairpins; which is easily adjustable to fit around any digit of any ordinary or average hand; and which is properly designed and constructed to support and spread a plurality of bobby-pins in substantially parallel spaced relation to one another, so the user can manipulate them individually with the hand that is free from the supporting and spreading device, so as to cooperate with the latter for spreading and removing each bobby-pin while it is quite near the hand that holds the hair-lock and supports the device that supports the remaining bobby-pins.

Another object of the invention is to provide an exceedingly simple and comparatively inexpensive device that effects the foregoing functions and advantages, and which is useful by persons who make their own coiffures and by operators in beauty shops and in barber shops.

Other objects and important features are pointed out or implied in the following details of description, in connection with the accompanying drawing in which:

Fig. 1 is a side-elevation of one of the dispensing and spreading supports according to this embodiment of my invention.

Fig. 2 is a view similar to Fig. 1, of the same device, but having its finger-engaging loop or annulus expanded to fit around a larger digit than could be passed thru the retracted loop of Fig. 1, this view also showing six bobby-pins in their pre-dispensing positions, and a seventh bobby-pin in a dispensing position, viz., spread and ready to be removed by either a longitudinal

2

upward movement or by a lateral rightward movement.

Fig. 3 is an enlarged sectional view along the line 3—3 of Fig. 2, and of a bobby-pin straddling the width of the hairpin-supporting arm and thereby having its prongs spread apart, preparatory to being grasped as shown at the right in Fig. 5.

Fig. 4 is an under-side view of the devices shown 10 in Fig. 2.

Fig. 5 is a view illustrating the approximate positions of the hands of a user of my invention which has one bobby-pin thereon; another bobby-pin being gripped between a finger and thumb of 15 the free hand that has removed the spread bobby-pin from the supporting and spreading arm and is keeping it spread preparatory to engaging it with a hair-lock (not shown), the arcuate broken line indicating the position of a scalp or crown 20 of a person's head with respect to the hands that manipulate the bobby-pins and support the hairpin dispenser and spreader.

Fig. 6 is a side elevation showing a modified form of the invention.

25 Referring to the drawing in detail, in which similar reference numerals refer to similar parts in the several views, the invention is described in detail as follows:

A single strip of pliable metal or other relatively rigid material has one end-portion formed in a loop or substantial annulus 7 which is expandable and retractable for adjustment to fit around a finger or thumb of any ordinary adult's hand. The other end-portion or arm 8 of this strip is preferably arcuate and formed with alternating thick and thin portions 9 and 10 that combine to form notches or grooves 11 across the lower side of the supporting arm 8, these grooves each being only slightly wider than the respective 30 hairpins whose lower prongs are to be seated therein, and these grooves being considerably spaced from one another, that is, sufficiently spaced from one another to permit a person to grasp any individual thus-supported hairpin or 35 bobby-pin and turn it to an upright position (as in Figs. 2 and 3) without interference by the ones that remain on the supporting arm 8. When a bobby-pin is thus turned into an upright position, its prongs are spread apart to a greater or less extent, by pushing it downward or pulling it 40 upward before tightening the grasp of the finger and thumb that holds it and retains the prongs in the thus-separated or divergent relation, as shown in Fig. 5, in readiness to be engaged with a relatively thick hair-lock.

The extreme and near-extreme end-portion 12 is preferably arcuate, so, when any bobby-pin is slid outward thereover, it will tend to close gradually, and the user's grasp will instinctively tighten to prevent the prongs from being spring-pressed to their unspread position. The unspread bobby-pins are indicated at 13, and the spread ones are seen at 13a.

While it is advantageous for the part 8 to be curved or arcuate so as to arch over the back of the user's hand to which it is attached, the invention is not limited to such curvature nor to other precise details of construction, for the invention is susceptible of numerous changes within the scope of the inventive ideas as implied and claimed.

As an instance of the above-mentioned changes, Fig. 6 is shown in inverted-U shaped or horse-shoe-shape. It is formed of a thin and relatively wide strip of metal which is relatively rigid or stiff while being somewhat springy and somewhat ductile or pliant. The middle portion 8a of the strip is scalloped to form notches 11a for receiving prongs of the respective hairpins which will be held in the notches by either or both spring-pressure of the hair-pins. The end-portions of this form (Fig. 6) are arcuate or concave at their sides 7a that face one another and constitute, in combination, a digit-engaging clamp or means to be spring-pressed against opposite sides of a thumb or finger of the user; the spring-pressure being exerted by the loop 8a, and this loop can be manipulated to increase or decrease the clamping pressure at 1a, or to adjust the clamp to conform to digits of different sizes.

I claim the following as my invention:

1. In a dispenser and spreader for hairpins and the like, a relatively rigid strip that is considerably wider than its major thickness and which has a series of grooves across one of its wider sides in considerably spaced relation to one an-

other, substantially as described, each of these grooves being wide enough to contain a prong of a hairpin while the latter is straddling and spring-clamping said strip, whereby a series of hairpins in such straddling and spring-clamping relation are considerably spaced from one another for a purpose specified.

2. In the structure defined by claim 1, each groove being only slightly wider than the prong to be contained therein so the latter is secured at a substantially definite distance from adjacent prongs contained in said series of grooves.

3. In the structure defined by claim 1, one end-portion of said strip being properly formed to provide means to engage with and be supported by a digit of a hand of a person whose other hand is free to clamp and manipulate any hairpin while in and out of said straddling engagement.

4. In the structure defined by claim 1, one end-portion of said strip being substantially annular and of a proper size to fit around a digit of a user's hand and support the laterally grooved arm adjacent to said hand.

5. In the structure defined by claim 1, one end portion of said strip being substantially annular and pliant so it can be expanded and contracted for adjusting it to conform to digits of different sizes, and so it can be conveniently and efficiently used by any normal adult person in the manner shown.

6. In the structure defined by claim 1, said strip including a loop in which said grooves are formed, the end-portions of the strip having concave sides facing toward one another in a proper relation to be fitted and spring-pressed against opposite sides of a digit of a hand of the user, said loop being of somewhat springy material so it serves as means to spring-press said concave sides towards one another.

CHARLES T. CALAFIORE.
